DAMPER CONTROL

Troy F. Duis and William H. Moerchen,
Streator, Ill.

Application April 19, 1945, Serial No. 589,232

12 Claims. (Cl. 236—15)

1

This invention relates to a damper and to an automatic control therefor. It has for one object to provide an automatic damper control which will operate in response to one or more variable conditions present in a furnace when combustion is occurring.

It has for another object to provide a damper control for use in connection with furnaces to which forced air is supplied and to cause the damper control to operate in response to variations in the supply of air.

Another object is to provide a damper control arranged to operate in response to variations in suction conditions within the smoke pipe of the furnace.

Another object is to provide means for operating a damper control in response to variations in the air supply to the furnace and in response to variations of conditions in the smoke pipe of the furnace.

Other objects will appear from time to time throughout the specification and claims.

This invention is illustrated more or less diagrammatically in the accompanying drawings, wherein:

Figure 1 is a diagrammatic side elevation illustrating one form of the device;

Figure 2 is a detailed front elevation on an enlarged scale, showing a latching mechanism;

Figure 3 is a sectional detail showing a modified form of piston controlling means; and

Figure 4 is a sectional detail showing a further modified form of piston controlling means.

Like parts are indicated by like characters throughout the specification and the drawings.

The invention, as shown, is illustrated diagrammatically in association with a furnace or combustion device and a blower or air-supplying means. As shown, the furnace is indicated diagrammatically at 1. The invention may be applied to almost any type of burning device. A smoke pipe 2 conducts away the smoke and gases which result from the combustion.

A blower 3 is associated with the furnace, which forces air to the furnace. The blower may also be associated with the means for supplying fuel, but these are not shown herewith, as they form no essential part of the present invention, which may be applied to a furnace burning solid or liquid fuel.

A damper 4 is fixed on a shaft 5, which is pivoted in the smoke pipe 2. A lever or arm 6 is also fixed on the shaft and arranged to tilt the damper. A counterweight 7 may be adjustably positioned on the arm 6, preferably adjacent one

2

end. At the opposite end the arm may be perforated, as at 8, or otherwise shaped to receive one end of a chain 9. The chain is also preferably provided with a ring or hook-engaging means 10. Below the ring a cable 11 may extend through a cylinder head 12 of a cylinder 13 which has a closed bottom 14. The cable is fixed within the cylinder to a piston 15.

Air from the blower 3 moves through a pipe or conduit 16 into the upper end of the cylinder 13, as shown in Figure 1. A pipe or conduit 17 is connected, as at 18, to the interior of the cylinder 13 and is connected, as at 19, to the interior of the smoke pipe 2. A stop 20 may be adjustably fixed upon the cable to limit the downward movement of the piston.

As the means for locking the damper in the open position, the ring 10 is arranged to be engaged over a hook 21. This hook may be carried on a support 22 mounted on the front of the furnace or boiler. As will be seen from Figure 2, the hook 21 is offset from the normally vertical position of the chain.

In Figure 3, instead of the piston and cylinder mechanism of Figure 1, a cylinder 23 having a head 24 and a closed bottom 25 may be used. This cylinder has mounted within it a closed bellows 26. The cable 11 passes through the cylinder head 24 and is secured to the bellows. The pressure conduit 16 is in communication with the cylinder 23, as at 27, and the suction conduit 17 is in communication with the interior of the bellows, as at 28.

In the modified construction of Figure 4, a cylinder 29 is used. This cylinder has a cylinder head 30 through which the cable 11 passes. It has a closed bottom 31. It is partially filled with a liquid 32. An inverted cup 33 is positioned within the cylinder 29 and floats in the liquid 32. The cable 11 is secured to the inverted cup. The pressure conduit 16 is in communication with the cylinder 29, as at 34, and the suction conduit 17 is in communication with the interior of the inverted cup 33, as at 35.

Although we have shown an operative form of our invention, it will be recognized that many changes in the form, shape and arrangement of parts can be made without departing from the spirit of the invention, and our showing is therefore to be taken as, in a sense, diagrammatic.

The use and operation of this invention are as follows:

The control is associated with a fuel burning device which for purposes of simplicity has been called a furnace, although it might be associated

with a stove or any equivalent means in which fuel is burned and in connection with which means are provided for furnishing air from a blower or its equivalent.

In any combustion device the products of combustion are discharged, and for purposes of simplicity the means or opening through which they are discharged is referred to as a smoke pipe. Some suction is produced in the smoke pipe. The device, whether it includes the cylinder of Figure 1, the bellows of Figure 3 or the dash-pot of Figure 4, operates in substantially the same manner.

When the fire under the furnace is not burning the parts will stand in substantially the position shown in full lines in Figure 1. They will also stand in this position when the fire is burning and the blower is inactive. Assuming now that combustion is taking place and that the blower is operating, air under pressure will be supplied through the conduit 16 to the cylinder above the piston, the bellows or the dash-pot. For some installations the connection 17 from the cylinder to the smoke pipe will be omitted.

Assuming for the present that the conduit 17 is as shown in Figure 1, when combustion takes place, suction is developed in the smoke pipe and hence suction is effective in the cylinder below the piston or the dash-pot or from within the bellows. Where these two forces are in effect, pressure from the blower and suction from the smoke pipe move the member to which the cable 11 is secured downwardly, and thus the lever 6 is rotated from the full line position of Figure 1 and the damper is progressively opened. When suction in the smoke pipe is reduced and the supply of air from the blower is reduced, the piston rises and the lever 6 rotates in counterclockwise direction under the influence of the counterweight 7. Since the piston or the equivalent members as shown in Figures 3 and 4 are moved as a combined result of variations in suction in the smoke pipe and variations in air pressure, the piston may move should one of these factors vary and the other remain constant.

As above pointed out, for some purposes and for some installations the conduit 17 may be omitted, and in that case the piston or equivalent members will move in response to variations in air pressure alone. Where that is the case and where the conduit 17 is omitted, some means for the escape of air from below the piston or from within the bellows or from below the dash-pot 33 must be provided. In the case of the structure of Figure 1, the closure plate 14 for the cylinder 13 would be omitted. In the case of the form of Figure 3 an opening to the air would be provided from below the bellows and in the case of Figure 4 a conduit from within the dash-pot member 33 to the outer air would be provided.

At some times and for some purposes it is desirable to latch the damper in the open position. The ring 10 and the hook 21 are provided for that purpose. At that time the ring is pulled downwardly, opening the damper, and the ring is moved somewhat to the side from the vertical line along which it will ordinarily move during operation of the device and is engaged upon the hook 21. Should an operator, having engaged the hook and ring, forget to disengage them, they will become automatically disengaged in the following manner: Assume that the ring 10 is engaged upon the hook 21 and that the apparatus is in operation. Sooner or later sufficient suction or sufficient air pressure or both will be effective

upon the piston to move it low enough to carry the ring 10 out of engagement with the latch hook 21.

As soon as that occurs, the chain 9, the cable 11 and the ring 10 will move again into the vertical position indicated in dotted lines in Figure 2 and the ring is thus away from the hook 21 and as the ring moves up and down with variations in the position of the apparatus, it moves along a line away from the latch hook and cannot be accidentally engaged upon it.

Should the chain, the cable or other associated parts break, the counterweight 7 will overbalance the opposite end of the arm 6 and will carry the damper 4 to an open position such as that indicated in dotted lines in Figure 1. The degree to which the damper may be moved in this direction should the chain be broken depends of course upon the clearance available for movement of the lever arm 6. In the installation shown here-with the clearance is sufficient to permit the arm 6 to move to a vertical position and thus to carry the damper to the full open position.

We claim:

1. In combination with a combustion apparatus having a smoke pipe and a blower, a damper for said combustion apparatus in said pipe, and means for automatically moving said damper, said means comprising a damper operating member provided with moving means tending, when free to do so, to move it in one direction, and means for moving it in the opposite direction, said means including a pressure responsive device, a connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the connection member in one direction as the pressure from the blower increases and as the suction in the smoke pipe increases, the moving means being effective to move the damper in the opposite direction as said pressure and suction decrease.

2. In combination with a combustion apparatus having a smoke pipe and a blower, a damper for said combustion apparatus in said pipe, and means for automatically moving said damper, said means comprising a damper operating member provided with moving means tending, when free to do so, to move it in one direction, and means for moving it in the opposite direction, said means including a pressure responsive device, a connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the connection member in one direction as the pressure from the blower increases and as the suction in the smoke pipe increases, the moving means being effective to move the damper in the opposite direction as said pressure and suction decrease, and a stop on said connection member effective to limit movement of said pressure responsive device in one direction.

3. In combination with a combustion apparatus having a smoke pipe and a blower, a damper for said combustion apparatus in said pipe, and means for automatically moving said damper, said

means comprising a damper operating member provided with moving means tending, when free to do so, to move it in one direction, and means for moving it in the opposite direction, said means including a pressure responsive device, a connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the connection member in one direction as the pressure from the blower increases and as the suction in the smoke pipe increases, the moving means being effective to move the damper in the opposite direction as said pressure and suction decrease, and means for latching said connection in one position, said means including a member in said connection and a latching member, the two being adapted to be engaged together, the latching member being positioned out of the line of normal travel of said connection.

4. In combination with a combustion apparatus having a smoke pipe and a blower, a damper for said combustion apparatus in said pipe, and means for automatically moving said damper, said means comprising a damper operating member provided with moving means tending, when free to do so, to move it in one direction, and means for moving it in the opposite direction, said means including a pressure responsive device, a connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the connection member in one direction as the pressure from the blower increases and as the suction in the smoke pipe increases, the moving means being effective to move the damper in the opposite direction as said pressure and suction decrease, and a stop on said connection member effective to limit movement of said pressure responsive device in one direction, and means for latching said connection in one position, said means including a member in said connection and a latching member, the two being adapted to be engaged together, the latching member being positioned out of the line of normal travel of said connection.

5. In combination with a combustion apparatus having a smoke pipe and a blower, a damper for said combustion apparatus in said pipe, and means for automatically moving said damper, said means comprising a damper operating member provided with moving means tending, when free to do so, to move it in one direction, and means for moving it in the opposite direction, said means including a pressure responsive device, a flexible connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the flexible connection member in one direction as the pressure from the blower increases and as the suction in the smoke pipe increases, the moving means being effective to move the damper in the

opposite direction as said pressure and suction decrease.

6. In combination with a combustion apparatus having a smoke pipe and a blower, a damper

- 5 for said combustion apparatus in said pipe, and
means for automatically moving said damper,
said means comprising a damper operating mem-
ber positioned outside of the smoke pipe provided
with moving means tending, when free to do so, to
10 move it in one direction, and means for moving
it in the opposite direction, said means including
a pressure responsive device, a connection mem-
ber between said pressure responsive device and
said damper moving means, a connection from
15 said blower in communication with one side of
said pressure operated device, and a connection
from said smoke pipe in communication with the
opposite side of said pressure responsive device,
whereby the said pressure responsive device is
20 caused to move the connection member in one
direction as the pressure from the blower in-
creases and as the suction in the smoke pipe in-
creases, the moving means being effective to move
the damper in the opposite direction as said pres-
25 sure and suction decrease.

7. In combination with a combustion appa-
ratus having a smoke pipe and a blower, a damper
for said combustion apparatus in said pipe, and
means for automatically moving said damper,
30 said means comprising a damper operating mem-
ber positioned outside of the smoke pipe pro-
vided with moving means tending, when free to
do so, to move it in one direction, and means
for moving it in the opposite direction, said
35 means including a pressure responsive device, a
connection member between said pressure re-
sponsive device and said damper moving means,
a connection from said blower in communica-
tion with one side of said pressure operated de-
40 vice, and a connection from said smoke pipe in
communication with the opposite side of said
pressure responsive device, whereby the said pres-
sure responsive device is caused to move the con-
nection member in one direction as the pres-
45 sure from the blower increases and as the suction
in the smoke pipe increases, the moving means
being effective to move the damper in the op-
posite direction as said pressure and suction de-
crease, and a stop on said connection member
50 effective to limit movement of said pressure re-
sponsive device in one direction.

8. In combination with a combustion appa-
ratus having a smoke pipe and a blower, a damper
for said combustion apparatus in said pipe, and
means for automatically moving said damper,
55 said means comprising a damper operating mem-
ber positioned outside of the smoke pipe provided
with moving means tending, when free to do so, to
move it in one direction, and means for mov-
ing it in the opposite direction, said means in-
60 cluding a pressure responsive device, a connec-
tion member between said pressure responsive
device and said damper moving means, a connec-
tion from said blower in communication with
one side of said pressure operated device, and
65 a connection from said smoke pipe in communica-
tion with the opposite side of said pressure re-
sponsive device, whereby the said pressure re-
sponsive device is caused to move the connection
member in one direction as the pressure from the
70 blower increases and as the suction in the smoke
pipe increases, the moving means being effective
to move the damper in the opposite direction
as said pressure and suction decrease, and a stop
75 on said connection member effective to limit

movement of said pressure responsive device in one direction, and means for latching said connection in one position, said means including a member in said connection and a latching member, the two being adapted to be engaged together, the latching member being positioned out of the line of normal travel of said connection.

9. In combination with a combustion apparatus having a smoke pipe and a blower, a damper for said combustion apparatus in said pipe, and means for automatically moving said damper, said means comprising a damper operating member positioned outside of the smoke pipe provided with moving means tending, when free to do so, to move it in one direction, and means for moving it in the opposite direction, said means including a pressure responsive device, a flexible connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the flexible connection member in one direction as the pressure from the blower increases and as the suction in the smoke pipe increases, the moving means being effective to move the damper in the opposite direction as said pressure and suction decrease, and means for latching said connection in one position, said means including a member in said connection and a latching member, the two being adapted to be engaged together, the latching member being positioned out of the line of normal travel of said connection.

10. In combination with a combustion apparatus having a smoke pipe and a blower, a damper for said combustion apparatus in said pipe, and means for automatically moving said damper, said means comprising a damper operating member positioned outside of the smoke pipe provided with moving means tending, when free to do so, to move it in one direction, and means for moving it in the opposite direction, said means including a pressure responsive device, a flexible connection member between said pressure responsive device and said damper moving means, a connection from said blower in communication with one side of said pressure operated device, and a connection from said smoke pipe in communication with the opposite side of said pressure responsive device, whereby the said pressure responsive device is caused to move the flexible connection member in one direction as the pressure from the blower increases and as the suction in the smoke pipe increases, the moving means being effective to move the damper in the opposite direction as said pressure and suction decrease, and a stop on said connection member effective to limit movement of said pressure responsive device in one direction, and means

for latching said connection in one position, said means including a member in said connection and a latching member, the two being adapted to be engaged together, the latching member being positioned out of the line of normal travel of said connection.

11. In combination with a combustion apparatus having a smoke pipe and a blower, a damper for said combustion apparatus in said pipe, and means for automatically moving said damper, said means comprising a damper operating member provided with moving means, and tending, when free to do so, to move it in one direction, and means for moving it in the opposite direction, said means including a pressure responsive device, a connection member between said pressure responsive device and said damper, moving means, a connection member from said blower in communication with said pressure responsive device, whereby the said pressure responsive device is caused to move the connection member in one direction as pressure from the blower increases, the moving means being effective to move the damper in the opposite direction as said pressure decreases, and means for latching said connection in one position, said means including a member in said connection and a latching member, the two being adapted to be engaged together, the latching member being positioned out of the line of normal travel of said connection.

12. In combination with a combustion apparatus having a smoke pipe and a blower, a damper for said combustion apparatus located in said pipe, and means for automatically moving said damper in response to variations in pressure conditions in said blower and in said smoke pipe, said means including a pressure responsive device, a connection to one side of said device from said blower, and a connection to the other side of said device from said smoke pipe, a part of said pressure responsive device being mounted for movement, and a connection from said movable part to said damper, whereby pressure variations within the blower or the smoke pipe will move said movable member and thereby will move the damper.
